Primary Examiner—Carol Rademaker*(74) Attorney, Agent, or Firm*—Alan A. Bornstein(57) **CLAIM**

The ornamental design for a bottle, as shown and described.

DESCRIPTION

FIG. 1 is a front and right side perspective view of my bottle;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof; and,

FIG. 7 is a left side elevational view thereof.

The dash-dash-dash broken lines shown in the drawings are for environmental use only and form no part of the claimed design.

The dot-dash-dot-dash broken lines shown in the drawings define the boundary of the claimed design.
